Primary Examiner — Eric Goodman*Assistant Examiner* — Luqman McNeil(74) *Attorney, Agent, or Firm* — Adli Law Group P.C.(57) **CLAIM**

I claim the ornamental design for a motorized ticket scraping device, as shown and described.

DESCRIPTION

FIG. 1 is a front elevational view of a motorized ticket scraping device according to the claimed design;

FIG. 2 is a top view of a motorized ticket scraping device according to the claimed design.

FIG. 3 is a bottom view of a motorized ticket scraping device according to the claimed design.

FIG. 4 is a front view of a motorized ticket scraping device according to the claimed design.

FIG. 5 is a back view of a motorized ticket scraping device according to the claimed design.

FIG. 6 is a left view of a motorized ticket scraping device according to the claimed Design; and,

FIG. 7 is a right view of a motorized ticket scraping device according to the claimed design.

1 Claim, 3 Drawing Sheets(56)
